BARRIER ALARM

Jay K. Livingston, Houston, Tex., assignor of one-half to Ben Battelstein, Houston, Tex.

Application June 9, 1941, Serial No. 397,335

3 Claims. (Cl. 200—52)

This invention aims to provide a simple means whereby a signal will be given when an attempt is made to open a Venetian blind or other barrier unlawfully.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Fig. 1 shows in elevation, a device constructed in accordance with the invention, parts being in section;

Fig. 2 is an elevation showing one member of the blind-retaining hook;

Fig. 3 is an elevation showing the complementary member of the hook;

Fig. 4 is a sectional view showing the hook structure in relation to a part of the blind;

Fig. 5 is a transverse section taken through the hook.

The letter B marks a barrier of any desired kind, such a Venetian blind, comprising slats 1 and a bottom rail 2 connected by vertical flexible bands 3.

In order that a signal circuit may be operated when the blind is raised, a hook structure is shown as mounted on a window sill 4 although the hook structure might be otherwise mounted. Moreover, the way in which the conductors of the signal circuit are arranged, and the way in which they are shielded from view, so that an intruder will not know that his actions are likely to be reported by a signal, will depend on whether the mechanism hereinafter described is incorporated in a building already constructed, or in one that is being newly erected.

The foregoing qualification being carried in mind, combined circuit closers and blind retainers 5, which may be headed screws, are mounted in the ends of the bottom rail 2, if the bottom rail is not already provided with such elements.

The hook structure, mounted on the window sill 4, if desired, is made up of complementary conducting members 6 and 7, which are alike, saving for the fact that the member 7 is provided at the inner end of its mouth 8 with an enlarged open-

ing 9. The members 6 and 7 of the hook structure have oppositely projecting feet 10, shown as held on the window sill 4 by securing elements 11, for example, screws.

5 A sheet of insulating material 12 is held tightly between the hook members 6 and 7, and has a laterally projecting U-shaped hub 14, received in the opening 9 of the hook member 7. The sheet 12 of insulating material conforms in outline to the hook members 6 and 7.

The structure last-mentioned preferably is duplicated at each end of the bottom rail 2 of the blind B.

The numeral 15 marks an electrical circuit, located as found convenient, and concealed as the details of installation may dictate. In the circuit 15 is interposed a source 16 of electrical energy, which may be either a battery or the usual source of house current. A signal 17 is interposed in the circuit 15 and is shown in the form of an audible signal, although a visible signal may be substituted if desired. A switch 18 is interposed in the circuit 15, and is under the control of an operator, to the end that the house owner may render the signal mechanism active or inactive, as he sees fit. The conductors of the circuit 15 may pass through an opening 19 in the sill 4 and be held beneath the feet 10 of the hook members 6 and 7, in electrical contact therewith, by means of the securing elements 11. The other hook structure can be brought into the circuit 15 by means of conductors 20 when the blind B is drawn down, and when the circuit closers 5 are engaged with the hook structures, the circuit closer 5 touches the hook member 6, but not the hook member 7, because the circuit closer is engaged with the insulating hub 14. So soon, however, as a prowler attempts to unhook the lower part of the blind, the part 5 rides out of the insulating hub 14 and touches both members 6 and 7 of the hook structure. The circuit 15 then is closed, the signal 17 will become active, and notice will be given that a breach of the house or other building is in progress.

45 As is common in connection with any device adapted to form part of a building, allowance must be made for the fact that, as to installation, the structure of the building has to be taken into consideration.

50 Having thus described the invention, what is claimed is:

1. In a circuit closer, a bridge, a fixedly-mounted hook structure including substantially-duplicated hook members located closely enough together to receive the bridge, and insulation

carried by one hook member, in the bight thereof, and engaging the bridge, the insulation being so limited in area that, when an effort is made to detach the bridge from the hook structure, the bridge will ride off the insulation, and come into electrical contact with conducting portions of both hook members.

2. A circuit closer constructed as set forth in claim 1, and wherein the insulation is a laterally-projecting hub, forming part of an insulating sheet which is bound between the hook members, said one hook member being provided with an enlarged opening in which the hub is received.

3. In a circuit closer, a bridge, a fixedly-mounted keeper structure including members located closely enough together to receive the bridge, and insulation carried by one keeper member and engaging the bridge, the insulation being so limited in area that, when an effort is made to detach the bridge from the keeper structure, the bridge will ride off the insulation, and come into contact with conducting portions of both keeper members.

JAY K. LIVINGSTON.
